UNITED STATES PATENT OFFICE.

JULIUS WEINBERGER, OF NEW YORK, N. Y., ASSIGNOR TO RADIO CORPORATION OF AMERICA, A CORPORATION OF DELAWARE.

METHOD AND APPARATUS FOR MINIMIZING SELF-EXCITED OSCILLATIONS IN VACUUM-TUBE SIGNALING DEVICES.

Application filed February 7, 1921. Serial No. 443,318.

This invention relates to a method and means for minimizing self-excited oscillations in vacuum tube signaling apparatus, but more especially in vacuum tube amplifiers, whether used in radio signaling, or in connection with land telegraphy, telephony, or submarine cables.

In telephony, telegraphy, or radio reception, it is frequently necessary to amplify minute amounts of electric energy, and for this purpose vacuum tubes of different types have been employed in various circuits. My present invention may be illustrated in connection with a vacuum tube amplifier which is especially useful in obtaining extremely high amplification of audio or radio frequency electromotive forces.

There are two main forms or types of amplifier circuits, known in the art respectively as "transformer coupled", and "resistance coupled", but a great deal of trouble has been experienced in the operation of such amplifiers, due to self-excited oscillations generated within the amplifying circuits. These oscillations give rise to a howling tone, or to irregular noises in the telephone receiver, which sometimes makes it impossible for the operator to hear anything else.

I have found that this trouble is due in large measure to capacity between various parts of the amplifier, the most troublesome capacity generally being that between the telephone leads in the final output circuit or the observer, and the input circuits of the amplifier.

Another source of trouble is found in the capacity between various elements of the amplifier circuits themselves, as the condensers, vacuum tubes, or resistances in a resistance coupled amplifier; oscillations occurring between intermediate vacuum tubes in the amplifier. These oscillations are of extremely high frequency, the elements of the oscillating circuits being the condensers between vacuum tubes and the lead wires. However, even though the oscillations themselves may be of inaudible frequency, they are usually broken up by the intermittent charging and leaking of the grid condensers, and so produce a tone or noise in the telephones.

The primary object of the present invention is to minimize or reduce the possibility of singing or self-excited oscillations by electrostatically shielding the input and output circuits and the apparatus contained therein, and also by electrostatically shielding each element within the amplifier from every other element by appropriate means.

To these ends, suitable apparatus and tubes for carrying out my method are illustrated in the accompanying drawings, in which,

Fig. 1 is a diagrammatic representation of a typical transformer coupled amplifier, of the ordinary type;

Fig. 2 is a similar view of a typical resistance coupled amplifier. These views in Figs. 1 and 2 are for the purpose of illustrating the association of elements which require shielding in accordance with my invention;

Fig. 3 is a diagrammatic representation of a capacitive coupling existing between output and input circuits in a typical amplifier circuit;

Fig. 4 is a diagrammatic representation of a transformer coupled amplifier like that shown in Fig. 1 with my invention applied thereto; and

Fig. 5 illustrates a resistance coupled amplifier like that shown in Fig. 2 with my invention applied thereto.

Referring to the drawings, and at first more especially to Fig. 1, a suitable source of energy to be employed (not shown), may be connected to the terminals A and B of an input transformer C, the secondary of which is connected to the grid D and filament E (input terminals) of a vacuum tube F of any suitable type, in this instance a tube of the three element type being shown, having the anode or cold plate G. Two tubes F are indicated in this instance, although the principles of the invention may be applied in any desired number of types.

The filaments E of the tubes F are energized from a common battery H and the necessary plate potential for operating all the tubes is provided by the battery J. The output terminals of the first tube F, that is the plate G and the positive end of

battery J, are connected to the primary of a second transformer K, the secondary of which is connected to the grid D and filament E of the second vacuum tube F. The 5 output terminals of this second tube F are connected to an electro-responsive device, as a pair of head telephones L, in which the energy is to be absorbed.

In the resistance coupled type of amplifier shown in Fig. 2, the source of energy 10 to be amplified (not shown), may be connected to the terminals O and P and is thus impressed across the input side, that is across the grid D and filament E of the 15 amplifying tube F, a condenser Q being connected in this instance in the lead O as shown. The output terminals of the second tube F are connected as shown to an energy absorbing device which may be the head 20 telephones L.

The troublesome capacity generally existing between the telephone leads, or the observer, in the final output circuit, and the input circuits of an amplifier, may be diagrammatically represented as in Fig. 3. In 25 this figure, the vacuum tube F may be considered as representing the numerous types of amplifier, it being assumed for purposes of illustration that the amplification of this 30 single tube F is substantially equal to that of all the tubes in an amplifier. That is, the entire aggregate of input circuit, amplifying tubes and output circuit, may be reduced to a single tube of equal amplification and with 35 the same or equivalent input and output circuits connected to it. The input circuits may be represented in Fig. 3 by the inductance L', resistance R', and capacity C', and the output circuit may be represented by the 40 inductance L², resistance R², and capacity C². The capacitive coupling existing between input and output circuits may be represented by the capacity C³. Theoretical 45 consideration of such a system will indicate that for given values of the input and output circuit constants, the higher the amplification of the tube F, the less will be the value of the capacity C³, required to produce self-excited oscillations. For high amplifications 50 this may be incredibly small. For example, with one winding of a transformer of the ordinary telephone repeater coil type connected to the input terminals of an amplifier having an overall voltage amplification 55 of about one hundred times, and with a pair of ordinary radio receiving telephones in the output circuit, the capacity between the observer wearing the telephones and the input transformer windings, even with the 60 observer several feet away, is sufficient to set up strong singing. With voltage amplifications of the order of five thousand times, self-excited oscillations are set up easily, regardless 65 of the constants of the input and output circuits, unless means are provided

for preventing or reducing the production of self-excited oscillations in the amplifying circuits.

My method of solving the problem deals largely with the elimination of capacity between various points in the circuits. As stated, the most troublesome capacity generally exists between the telephones in the output circuit and the observer, and the apparatus of the input circuit. 70

As shown in Fig. 4, I overcome this difficulty by surrounding the telephone cords with a shield preferably of copper braid T, as shown in Figs. 4 and 5, and by connecting the metal caps and metal head band U 80 of the telephones L to the shield T around the cords, and in general taking every precaution to obtain a complete shield around all parts of the output circuit. This shield may then be connected to earth, or to a filament lighting battery H of the amplifier. In this way, the capacity between final output and input circuits is not only reduced substantially to zero, but there is interposed 85 between the observer and the output circuit a grounded shield, so that the observer is no longer capacitively connected to the output circuit via the telephones, and thus any capacity between the observer and input circuit is rendered substantially harmless. 90

The oscillations between various elements of the amplifier circuits themselves, as for instance the condensers, resistances, and vacuum tubes, may be eliminated by placing each amplifying element in a metal box 100 V, preferably of copper and suitably grounded. An amplifying element may consist of a vacuum tube F and the condenser and resistances with which it is immediately associated as illustrated in Figs. 4 and 5. By means of the metal boxes or metal shields V, a multi-step amplifier is produced in which each vacuum tube F with its immediate plate and grid circuit elements is shielded from the other vacuum tubes with 105 their plate and grid elements, and mutual capacity between the various steps of the amplifier reduced substantially to zero. 110

The shielding between vacuum tubes is not always necessary, provided the required 115 amplification is fairly low. In this case, however, it is desirable to enclose the vacuum tubes and their associated amplifier circuit elements in a metal box V so as to reduce mutual capacity between the vacuum tube circuits and the input circuit to substantially zero. The shielded telephones L may then be brought out of the amplifier case or box V as indicated in Figs. 4 and 5. Capacitive coupling between input circuit, 120 the elements of the amplifier and the output circuit is thus minimized or effectually prevented. 125

In case shielding of the output circuit is difficult, that is, in case the output of the 130

amplifier is to be impressed on a piece of apparatus which is larger than can be conveniently shielded, substantially the same results may be accomplished by shielding the 5 transformers C and K in Fig. 4. As shown, a metallic grounded shield W is inserted between the primary and secondary windings, so that no capacitive coupling exists between these windings and the entire transformer 10 former is placed inside a metallic box or shield X preferably of copper, so that no capacity exists from the windings to external objects. By connecting one such transformer C between input circuit and 15 amplifier as shown in Fig. 4, and a second similar transformer K between the output side of the amplifier and the circuit in which the energy is to be absorbed, the capacitive coupling between input and output circuits 20 may be reduced to practically zero.

The circuits of the lighting batteries H need not be shielded since these circuits are ordinarily grounded in any event, but I have found it generally advisable to provide 25 electrostatic shields for all the other circuits and lead wires of the amplifier, and as shown in Figs. 4 and 5 the said circuits and lead wires are covered with the shields of copper braid T as indicated for the telephone cords.

I claim and desire to obtain by Letters Patent the following:

1. In a telephone receiver circuit the combination of telephone cords, an amplification 35 circuit and means for shielding said cords from extraneous electrical influences comprising a metallic shield enclosing said cords substantially throughout their length and an electric connection between said shield and 40 said amplification circuit.

2. The combination of telephone cords, a low potential circuit, means for shielding the cords from extraneous electrical influences, said means including a metallic shield, 45 an electrical connection between the shield and the shell of the telephone receiver and an electrical connection between the shield and low potential circuit.

3. In a system for amplifying feeble 50 electrical currents, the combination with a signal amplifying device, a low potential circuit in said signal amplifying device, a signal responsive device, conductors connecting said devices, a shield surrounding said 55 conductors substantially throughout their length, and a connection between said shield and said low potential circuit.

4. A high power radio receiving amplifier comprising an electron tube having grid, 60 filament and plate electrodes, a telephone receiver actuated by said amplifier, and means for shielding the telephone receiver from extraneous electrical influences and reducing regenerative effects, said means including a metallic shield surrounding the telephone

conductors substantially throughout their length and a connection between said shield and one of said electrodes.

5. A high power radio receiving amplifier, a telephone receiver associated therewith 70 and means for shielding the telephone receiver from extraneous electrical influences, said means including a metallic shield surrounding the telephone conductors, and an electrical connection between the shield and the telephone receiver.

6. A high power radio receiving amplifier having a low potential circuit, a telephone receiver associated therewith, conductors connecting said receiver with said amplifier 80 and means for shielding the telephone receiver from extraneous electrical influences, said means including a metallic shield surrounding the telephone conductors and an electrical connection between the shield and the low potential circuit.

7. A high power radio receiving amplifier having a low potential circuit, a telephone head set associated therewith, and means for shielding the telephone head set 90 from extraneous electrical influences, said means including a metallic shield surrounding the telephone conductors, and electrical connection between the shield and the telephone head set, and an electrical connection 95 between the shield and the low potential circuit.

8. In a radio receiving apparatus the combination of a thermionic vacuum tube amplifier, an input circuit, an output circuit, reproducing means in said output circuit and 100 means surrounding the conductors of said output circuit and extending substantially throughout the length thereof for shielding said reproducing means from extraneous 105 electrical influences and regenerative effects.

9. In a radio receiving apparatus the combination of a plurality of thermionic vacuum tubes having grid, filament and plate electrodes, circuits interconnecting said electrodes, an output circuit including a plate 110 electrode, telephone receivers and a source of potential and means surrounding the conductors of said circuit and extending substantially throughout the length thereof for 115 shielding said telephone receivers from extraneous electrical influences and regenerative effects.

10. In a radio receiving apparatus the combination of a plurality of thermionic 120 vacuum tubes having grid, filament and plate electrodes, circuits interconnecting said electrodes, a source of potential for heating said filament electrodes, an output circuit including a plate electrode, telephone receivers and a source of potential and means connected to said source of filament potential 125 surrounding the conductors of said circuit substantially throughout their length for shielding said telephone receivers from ex- 130

traneous electrical influences and regenerative effects.

11. In a radio receiving apparatus the combination of a thermionic vacuum tube amplifier, an input circuit, an output circuit, reproducing means in said output circuit and means maintained at ground potential surrounding the conductors of said output circuit and extending substantially throughout the length thereof for shielding said reproducing means from extraneous electrical influences and regenerative effects.

12. In a radio receiving apparatus the combination of a plurality of thermionic vacuum tubes having grid, filament and plate electrodes, an output circuit including a plate electrode, telephone receivers and a source of potential and means surrounding the conductors of said circuit and extending substantially throughout the length thereof and connected to said source of potential

for shielding said telephone receivers from extraneous electrical influences and regenerative effects.

13. In a radio receiving apparatus, an electron tube amplifier comprising a plurality of electron tubes having grid, filament and plate electrodes, an input circuit, an output circuit, a responsive device connected in said output circuit, conductors for electrically connecting said device and said output circuit, and means for shielding said conductors from extraneous electrical influences and regenerative action with said input circuit comprising a flexible metallic shield surrounding the conductors and extending substantially throughout their length, and an electrical connection between the shield, the responsive device, and one of said electrodes.

JULIUS WEINBERGER.
